UNITED STATES PATENT OFFICE.

HEYMAN ROSENBERG, OF NEW YORK, N. Y.

AUTOMOBILE-WRENCH COMBINATION.

1,353,496.

Specification of Letters Patent. Patented Sept. 21, 1920.

Application filed August 14, 1919. Serial No. 317,417.

To all whom it may concern:

Be it known that I, HEYMAN ROSENBERG, a citizen of the United States of America, residing at New York city, county and State 5 of New York, have invented certain new and useful Improvements in Automobile-Wrench Combinations, of which the following is a full, clear, and exact description.

This invention relates to improvements in wrenches, or rather to a novel arrangement 10 of a set of wrenches especially arranged for automobilists. One of the objects of my invention is to provide a set of wrenches assembled in a suitable neat-appearing case, 15 said wrenches being at all times retained by the case whether in use or not. The wrenches are arranged so that any one of them may be moved to project from the case sufficiently to engage a nut. When the 20 wrenches are not in use, they will be concealed by the case, which may be packed away in any suitable receptacle or even carried in a pocket.

In the drawing, which form part of this 25 specification,—

Figure 1 illustrates in elevation, partly in section, one form of my improvement;

Fig. 2 illustrates in elevation another form of my invention;

Fig. 3 is a sectional plan view of the form 30 of my device illustrated in Fig. 1;

Fig. 4 is a longitudinal sectional view of the form illustrated in Fig. 1, illustrating one of the wrenches extended for use; and

Fig. 5 is a sectional plan view of the form 35 of my device illustrated in Fig. 2.

My improvement consists of a casing 6 containing, in this instance, a plurality of double-end wrenches, 7, 8, 9, 10 and 11, and 40 a double-ended screw-driver 12. Each wrench and the screw-driver, is provided with a slot 13 through which a retaining bolt 14 passes, said bolt having a threaded end 15 to engage a threaded opening 16 in 45 one of the walls of the casing 6. The bolt 14 is provided with a head 17 having a shoulder 18 to bear against the adjacent tool, be it the screw-driver 12 or a wrench, the arrangement of the tools being immaterial. When the bolt 14 is screwed down, 50 the tools will be firmly held in either an extended or retracted position. Should any one of the wrenches be needed, the bolt 14 will be loosened and the desired wrench 55 moved out as indicated in Fig. 4, after which the bolt 14 will be tightened to hold the ex-

tended wrench while it is being used. The same operation would, of course, be performed should I desire to use the screw-driver. Each wrench and screw-driver is 60 cut away as at 19 and 20 to lighten it, but I prefer to leave projections 21 to provide guides for the tools while being moved in or out. The guides or projections will maintain the tools at all times in alinement or in 65 parallelism with the axis of the casing. When a tool is moved out, the guides adjacent the projecting end will not leave the casing, as can be seen in Fig. 4. Hence, the tools when in use will be firmly supported. It will, of course, be understood 70 that a number of different size wrenches can be provided, especially when double-ended wrenches are used. The wrenches may be removed from the casing and used if desirable by removing bolt 14. I do not limit myself to the proportions herein employed, as they may be changed to suit conditions. In the form illustrated in Figs. 2 and 5, the tools indicated by 22 will be provided with 75 notches 23 and 24, and the casing 25 will be provided with a cutaway portion or opening 26 in order that the notches 23 and 24 can be engaged by the fingers to move any one of the wrenches outwardly. In this form, I 80 may employ a bolt such as 14 and for the same purpose, or I may movably secure the wrenches by means of a post 27, which is headed over at each end, said post passing through a slot 28 in each tool. It will be of 85 course understood that a casing such as 6 may be provided with tools other than wrenches, gages for instance, or files of different styles.

To prevent the screw-driver from slipping after it has been extended for use, I provide at each end of the slot 13 in the screw-driver a somewhat larger opening 13^a to receive the shoulder 18 of the bolt 14 when said bolt is screwed down to fasten the 95 screw-driver. After shoulder 18 has engaged an opening 13^a, the screw-driver will not slip when put to use. The slots 13 in the wrenches are not ordinarily enlarged at the ends. The slot 28 in the screw-driver 100 illustrated in Fig. 5, will be enlarged at the ends, as at 28^a.

Having described my invention, what I 105 claim is:

1. The combination of a casing having an 110 opening in the side thereof, a plurality of slidably mounted tools within the casing,

each tool being provided with a notch located in line with said opening, for the insertion of the fingers to extend said tools.

- 5 2. The combination of a casing, a tool slidably retained thereby and arranged for extension therefrom, said tool being provided with a slot, the slot being enlarged at each end, a retaining bolt passing through said casing and said slot, and a shoulder carried by the bolt arranged to engage either of the enlarged ends of said slot when the tool is extended for use, substantially as and for the purpose set forth.
- 10 3. In combination with a casing, a tool slidably mounted therein and adapted for

extension therefrom, the tool having a cut-away portion at its side edges to provide a plurality of alined projections bearing against the inner wall of the casing and arranged to maintain the tool in parallelism 20 with the longitudinal axis of the casing, and means to secure the tool in retracted or extended position.

Signed at New York city, N. Y., this 12th day of August, 1919.

HEYMAN ROSENBERG.
